(57) **CLAIM**

The ornamental design for a rice mold, as shown and described.

DESCRIPTION

FIG. 1 is a perspective view of a rice mold;
FIG. 2 is a front view of the rice mold of FIG. 1, a back view being a mirror image thereof;
FIG. 3 is a right side view of the rice mold of FIG. 1, a left side view being a mirror image thereof;
FIG. 4 is a top view of the rice mold of FIG. 1;
FIG. 5 is a bottom view of the rice mold of FIG. 1;
FIG. 6 is a cross-sectional view thereof, taken along line 6-6 in FIG. 4;
FIG. 7 is a cross-sectional view thereof, taken along line 7-7 in FIG. 4; and,
FIG. 8 is a cross-sectional view thereof, taken along line 8-8 in FIG. 4.

1 Claim, 8 Drawing Sheets
